ISAAC C. POPPER, OF NEW YORK, N. Y., ASSIGNOR TO BASIC PRODUCTS CORPORATION,
OF NEW YORK, N. Y., A CORPORATION OF DELAWARE.

COLLAPSIBLE FIELD STOVE.

1,423,252.

Specification of Letters Patent. Patented July 18, 1922.

Application filed August 24, 1918. Serial No. 251,329.

To all whom it may concern:

Be it known that I, ISAAC C. POPPER, a citizen of the United States, residing at New York city, in the county of New York and State of New York, have invented certain new and useful Improvements in Collapsible Field Stoves, of which the following is a specification.

My invention relates to an improvement in collapsible field stoves. The object is to provide a portable knock-down stove adapted for general use, but more particularly for field and army use, and it consists in a top upon which the cooking is done and within which the fuel is placed and ignited, removable legs, and an oven or shelf, all of which can be taken apart and assembled in a comparatively small space, so that the stove can be conveniently moved from place to place or set up at any point, whether out or indoors, and used as an ordinary stove, and when outdoors in all kinds of weather without the slightest danger of smoke or explosion or the flame blowing out even in a high wind.

This invention consists in a stove which includes a top, bottom, sides and door, within which the fuel is adapted to be placed, the sides having perforations for the supply of oxygen and the escape of the products of combustion, and legs detachably secured to the stove, as well as an oven or shelf, and both detachably supported beneath the stove.

In the accompanying drawings:

Figure 1 is a view in perspective showing the oven attached;

Figure 2 is a horizontal section through the stove;

Figure 3 is a transverse vertical section through the construction shown in Figure 1;

Figure 4 is a sectional view similar to Figure 3 showing a shelf in lieu of an oven; and

Figure 5 is a view in perspective of the removable shelf.

The stove portion includes the top 1, upon which the cooking is done, the bottom 2, the perforated ends and sides 3 and 4 respectively, and the perforated door 5, which is preferably connected to the downwardly-turned flange 6 on one edge of the bottom by means of hinges 7. The door ordinarily may be left open, but when closed it is held

by the buttons 7' or some similar fastening means.

Within the stove and on the bottom, holders 8 somewhat in the form of horse-shoes are placed to receive the cans of fuel. The fuel employed is preferably solidified alcohol, which is adapted to be burned directly from the cans, they being opened, and upon the application of a match there-to the fuel is ignited and the stove is in operation.

The legs 10, 10, four in number, are screw-threaded at their upper ends, and are inserted through holes 11 in the bottom-plate of the stove and are adapted to be screwed into the threaded sockets 12 a greater or less distance, thus enabling the operator to adjust them to any irregularities in the ground or floor in setting up the stove.

An oven 13 is removably mounted beneath the stove, it being detachably fastened by any suitable means, such as buttons 13' similar to those previously described (7'). Other approved means of fastening, of course, might be employed.

In lieu of the oven a shelf 14 might be used. This is provided with slots 15 which receive and straddle the legs and rest upon pins 16 extending through the legs.

Handles 17 may be provided for the legs for convenience to facilitate screwing them in and out.

Thus I have provided a stove of few and simple parts which may be easily and quickly dismembered and stored in small compass or re-assembled, whereupon it is effective in either field or domestic use; and it is evident that more or less slight changes might be made, such for instance as the omission of the bottom plate and possibly the sides and ends, although in the most approved form of the invention they are preferred as they house the fuel and protect the flame and prevent its being extinguished in high winds; and hence I do not wish to limit myself to that construction illustrated and described.

I claim:

1. A collapsible field stove including top, bottom, perforated sides, ends and door, the top and bottom relatively close to each other, whereby a relatively low and flat stove portion is formed which is adapted to receive therein cans of solidified fuel where by the flame therefrom is at the proper dis-

tance from the top, and legs extending loosely through the bottom and removably secured to the lower side of the top, and constituting the sole means of support for 5 the stove.

2. A collapsible field stove including a stove portion which is composed of a top, bottom, perforated ends, sides and door, and within which the heating medium is 10 adapted to be enclosed, and by which the flame thereof is protected from the wind and drafts, the top portion having depending threaded sockets, and the bottom portion provided with holes opposite each socket, 15 and removable legs insertable through said holes and having threaded ends which screw into the sockets, and constituting the sole means of support for the stove.

3. A collapsible field stove including a 20 stove portion which is composed of a top, bottom, perforated ends, and sides, and within which the heating medium is adapted to be enclosed, and by which the flame thereof is protected from the wind and 25 drafts, the top portion having depending sockets, and the bottom portion provided with holes opposite each socket, removable legs insertable through said holes into the 30 sockets, and means detachably supported on the legs below the stove portion through which the legs pass to serve as an oven or a shelf.

4. A collapsible field stove including a stove portion which is composed of a top,

bottom, perforated ends, sides and door, and 35 within which the heating medium is adapted to be enclosed, and by which the flame thereof is protected from the wind and drafts, the top portion having depending threaded 40 sockets, and the bottom portion provided with holes opposite each socket, removable legs inserted through said holes and having threaded ends which screw into the sockets, and means detachably supported on the legs below the stove portion through which the 45 legs pass to serve as an oven or a shelf.

5. A collapsible field stove including a stove portion which is composed of a top, bottom, perforated ends, and sides, and within which the heating medium is adapted 50 to be enclosed, and by which the flame thereof is protected from the wind and drafts, and holders on the bottom of the stove adapted to removably receive the fuel cans at just the right position and distance from 55 the top.

6. A collapsible field stove including an imperforate top and bottom, perforated sides, ends and door, the door extending approximately the full length of one side, depending sockets from the lower surface of the top and the bottom having holes immediately beneath these sockets and legs insertable through the holes in the bottom and 60 adjustably connected with the depending 65 sockets.

In testimony whereof I affix my signature.
ISAAC C. POPPER.
